UNITED STATES PATENT OFFICE

WILLIAM A. BUSIEK, OF BELLEVILLE, ILLINOIS

RANGE

Application filed March 25, 1927. Serial No. 178,313.

The object of my device is to devise a range oven frame and door hingedly secured thereto. A further object is to make a range door having concealed hinges, that is to say, hinges that are not visible from the outside and front of the range. A still further object is to hingedly secure a range door to its frame so that when the door is in its closed position, there will be no appreciable space or opening 10 between the hinge side of the door and the contiguous frame portion.

A still further object is to make a device of the character described so that when the door is secured to the hinge element, the hinge element will not become disengaged. Stating it negatively, in assembling the door and frame, the securing of the door to the hinge element secures the hinge element in the frame preventing its dislodgement when in 20 use. A further object is to design the oven door so that although it comes in practical contact with the frame, it is not in actual contact therewith, so that the enameled portion of the door does not come in contact 25 with the metal portion of the frame. This is important because it prevents the chipping of the enamel, which chipping may commence in a concealed place but when once commenced will continue to a visible place. I 30 have provided special means for securing the door to the hinge element so that there can be no relative movement between the hinged element and the door. My device is so constructed that when the door is in its open position, that is, in a horizontal plane, it is in the same plane with the bottom of the oven, thereby facilitating the movement of cooking 35 utensils from the door into the oven. By the construction that I have devised, the door 40 may be held in any position automatically.

My device is made of few and simple parts that lend themselves readily to multiple production and can be cheaply made, easily assembled, and easily taken apart for repairs. 45 By the use of my device the door and frame may be enameled separately, the two being assembled after the enameling by the simple insertion of the hinge element into the frame and the securing of the door to the hinge 50 element.

With these and other objects in view, my invention has relation to certain novel features of construction and arrangement of parts as will be hereinafter more fully described, pointed out in the claims and illustrated in the drawing, in which

Fig. 1 is a front elevation of the front frame of an oven, showing the door in closed position.

Fig. 2 is a rear elevation of the structure 60 shown in Fig. 1.

Fig. 3 is a sectional elevation on the line 3—3 of Fig. 1. Fig. 4 is a sectional elevation of the frame and door showing the door in a partially open position. Fig. 5 is a perspective view of the hinge element. Fig. 6 is a perspective view of one corner of the frame into which the hinge element fits. Fig. 7 is a sectional elevation on the line 7—7 of Fig. 2. Fig. 8 is a sectional elevation similar to Fig. 7, showing the door in open position, and Fig. 9 is a sectional elevation on the line 9—9 of Fig. 2.

Numerals 10 designates the frame, numeral 11 the door, having the handle 12. The frame 10 has the flanges 14 formed integral therewith, the thickness of the frame being such that when the door 11 is positioned therein and its outer rectangular edges are in practical contact with the flange 14 that the door and the outer surface of the frame will be flush with each other.

There will be no protuberances either on the door or frame extending externally outwardly. In the right and left hand lower corners of the frame, the flanges 14 are cut away, leaving the rectangular openings 14^a best shown in Fig. 6. The ends of the hinge element are of such size as to fit into these rectangular openings 14^a. The hinge element is inserted into the frame from the rear so that the shank 16 is positioned against the outside face of the flange 14. In the shank 16 of the hinge element are formed the holes 17. On the lower inner surface of the door 11 are formed the cylindrical projections 18. The door 11 is secured to the hinge element by inserting the cylindrical projections 18 in the holes 17. A hole 20 is tapped in each of the cylindrical projections 18. Numeral

19 designates a bolt that is passed through the holes 17 in threaded engagement in the holes 20. The head of the bolt 19 is larger than the hole 17. A slot is cut in the head of the bolt 19 so that a screw-driver may be used to secure the bolt head tightly against the shank 16 of the hinge element around the holes 17. It will be seen therefore that in order to secure or detach the door from the hinge element that it is only necessary to secure or detach the two bolts 19. When the door is attached to the hinge element, it will be seen that it will not be possible to remove the door from the frame. An even positive predetermined rotation of the hinge element in the frame is secured by means of the conformation of the ends and the conformation of the frame in and around the two lower corners below and opposite the rectangular slots 14^a 20. cut in the flange 14 at these points. At these points in the frame element is formed integral the cavity 21, which cavity has the formation of the segment of a cylinder with the recess 22 at its bottom which ledge 22 25 acts as a support for the hinge element, as will be subsequently described. The ends of the hinge element are formed with a curved surface 23, which when the hinge element is in position in the frame 10 is in rotating frictional engagement in the slot 14^a. Numeral 24 designates a head formed on the ends at the end of the curved surface 23 as clearly shown in the drawing. The purpose of the head 24 is to limit the rotation of the hinge 30 element to a horizontal plane. The outer surface of the head 24 presents a curved surface 25.

On the frame adjacent the corners in which the ends rotate are formed projections 26 to 40 which are secured at each corner a leaf spring 27, the free end of which is in sliding engagement on the surface 25 of the head 24. The leaf spring 27 holds the hinged element and hence the door 11 in any position to which 45 the door is moved.

24' designates a curved surface terminating in bearing edge 15' to rest on ledge 22.

What I claim and mean to secure by Letters Patent is:

50. 1. An oven frame, an oven door, a concealed hinge element having ends including curved surfaces terminating in a bearing edge, said element secured to the door for rotation within the frame, securing means comprising cylindrical projections secured to the inner lower face of said door, said projections being positioned in holes, which holes are formed in said hinge element, and bolts positioned in threaded engagement in holes 55 formed in said cylindrical projections.
60. 2. In combination with a frame having a rectangular opening, a door, a hinge element secured to the door for rotation within the frame, the ends of the hinge element being 65 curved for rotation through said opening, a

head formed at the termination of said curve with a stop and a leaf spring secured to the frame at one end and having its free end in sliding engagement with said head.

3. In combination with a frame, a hinge element having reversed duplicate ends, each including curved surfaces terminating in a bearing edge, a door supported by said hinge element for rotation therewith, and ledges on the frame to receive the bearing edges.

In testimony whereof I affix my signature. 75
WILLIAM A. BUSIEK.
